(57) **CLAIM**

The ornamental design for an LED matrix display, as shown and described.

DESCRIPTION

FIG. 1 is a front perspective view of an LED matrix display according to a first embodiment of the present disclosure.

FIG. 2 is a front elevation view thereof.

FIG. 3 is a rear elevation view thereof.

FIG. 4 is a first side view thereof.

FIG. 5 is a second side view thereof.

FIG. 6 is a top plan view thereof.

FIG. 7 is a front elevation view thereof illustrating the LED matrix display in a gaming environment.

FIG. 8 is a front perspective view of an LED matrix display according to a second embodiment of the present disclosure.

FIG. 9 is a front elevation view thereof.

FIG. 10 is a rear elevation view thereof.

FIG. 11 is a first side view thereof.

FIG. 12 is a second side view thereof.

FIG. 13 is a top plan view thereof.

FIG. 14 is a front elevation view thereof illustrating the LED matrix display in a gaming environment.

FIG. 15 is a front perspective view of an LED matrix display according to a third embodiment of the present disclosure.

FIG. 16 is a front elevation view thereof.

FIG. 17 is a rear elevation view thereof.

FIG. 18 is a first side view thereof.

FIG. 19 is a second side view thereof.

FIG. 20 is a top plan view thereof.

FIG. 21 is a front elevation view thereof illustrating the LED matrix display in a gaming environment.

FIG. 22 is a front perspective view of an LED matrix display according to a fourth embodiment of the present disclosure.

FIG. 23 is a front elevation view thereof.

FIG. 24 is a rear elevation view thereof.

(Continued)

FIG. 25 is a first side view thereof.
 FIG. 26 is a second side view thereof.
 FIG. 27 is a top plan view thereof.
 FIG. 28 is a front elevation view thereof illustrating the LED matrix display in a gaming environment.
 FIG. 29 is a front perspective view of an LED matrix display according to a fifth embodiment of the present disclosure.
 FIG. 30 is a front elevation view thereof.
 FIG. 31 is a rear elevation view thereof.
 FIG. 32 is a first side view thereof.
 FIG. 33 is a second side view thereof.
 FIG. 34 is a top plan view thereof.
 FIG. 35 is a front elevation view thereof illustrating the LED matrix display in a gaming environment.
 FIG. 36 is a front perspective view of an LED matrix display according to a sixth embodiment of the present disclosure.
 FIG. 37 is a front elevation view thereof.
 FIG. 38 is a rear elevation view thereof.
 FIG. 39 is a first side view thereof.
 FIG. 40 is a second side view thereof.
 FIG. 41 is a top plan view thereof; and,
 FIG. 42 is a front elevation view thereof illustrating the LED matrix display in a gaming environment.
 The shade lines in the Figures show contour and not surface ornamentation. The broken lines in the Figures show portions of the support structure and its surrounding environment that form no part of the claimed design.
